UNITED STATES PATENT OFFICE.

LAURENCE J. BERKELEY, OF MILWAUKEE, WISCONSIN.

RAIL ANCHOR.

Application filed April 3, 1922. Serial No. 549,019.

To all whom it may concern:

Be it known that I, LAURENCE J. BERKELEY, a citizen of the United States, residing at Milwaukee, in the county of Milwaukee 5 and State of Wisconsin, have invented certain new and useful Improvements in Rail Anchors, of which the following is a specification, reference being had to the accompanying drawing, forming a part thereof.

10 This invention relates to devices for preventing the longitudinal creeping movement of railway rails.

Its main objects are to provide a simple and strong device of this class which can be 15 quickly and easily applied to rails and when applied will be effective and reliable in operation; which will not be loosened by the passage of trains or by changes in temperature; which will readily adapt itself to ordinary 20 variations in rail bases; the grip of which on the rails will be tightened by a slight longitudinal displacement of the rails on the ties; and generally to improve the construction and operation of devices of this 25 class.

It consists in the construction, arrangement and combination of parts as herein-after particularly described and pointed out in the claims.

30 In the accompanying drawing like characters designate the same parts in the several figures.

Figure 1 is a vertical longitudinal section on the line 1—1, Fig. 2, of a rail anchor embodying the invention as applied to a rail base which is shown in cross section; Fig. 2 is a plan view of the same, the rail being shown in horizontal section through the web and a portion of tie against which the anchor abuts being shown; Fig. 3 is an end elevation of the anchor as viewed from the right relative to Figs. 1 and 2, in connection with portions of a rail and tie; Fig. 4 is a view similar to Fig. 1, of a modification, 45 partly in side elevation and partly in vertical longitudinal section, on the line 4—4, Fig. 5, in connection with a rail base to which it is applied and which is shown in cross section; Fig. 5 is a plan view of the modified 50 anchor shown in Fig. 4, and parts of a rail base and tie; and Fig. 6 is a cross section of the modified anchor on the line 6—6, Fig. 4.

Referring to Figs. 1 to 3 inclusive, showing a preferred embodiment of the invention, the anchor comprises a rigid bar or yoke 1, adapted to span or extend across and fit the under side of a rail base 2, and formed or provided at one end with a jaw 3, fitting over one edge of the rail base and 55 at the other end opposite the other edge of the rail base, with a fulcrum seat or key bearing 4. It is also formed adjacent the bearing 4 and below the top of the bar with a key deflecting and straining bearing 5, 60 preferably formed with a convex or inclined face for engagement with a spring key to facilitate forcing the key into place, as shown in Fig. 1, and as hereinafter explained. The bar or yoke 1 may be made of malleable iron, 65 and for the sake of strength and lightness, is preferably flanged or of channel shape in cross section. It is formed in the web between the key bearings 4 and 5, with an 70 opening to receive the key and at or adjacent one end with a laterally projecting abutment 6, for engagement with the side of a tie 7, as shown in Figs. 2 and 3. The abutment 6 is preferably formed as shown in Fig. 2, with a convex or rounded face, for 75 proper and effective engagement with the tie when the bar or yoke assumes different positions on the rail base. The abutment 6 is braced and strengthened by a vertical web or flange 8, disposed transversely to the 80 bar 1.

A spring key 9, preferably of tapering and bowed or curved shape, as shown in Fig. 1, is adapted to be inserted and sprung or forced transversely to the length of a rail 90 into place between the fulcrum seat or bearing 4 and the opposite edge of the rail base and against the deflecting and straining bearing 5, and when the parts of the anchor are assembled on a rail base, as shown in Fig. 1, to exert a yielding pressure against the rail base towards the jaw 3, thereby subjecting the bar or yoke 1 to tension tending to draw the jaw towards the key and to 95 yieldingly grip the rail base between the jaw and the key with sufficient force under varying conditions, to prevent the bar or yoke from slipping on the rail base or the rail base from slipping on the bar or yoke.

The key 9 is formed in the inner edge adjacent its larger end, with a notch 10, to en-

gage with the upper corner of the adjacent rail base flange and hold it in place thereon.

To apply the anchor to a rail, the bar or yoke 1 is placed underneath the rail base with the abutment 6 against the side of a tie, and the jaw 3 is driven or forced transversely to the rail into engagement with one edge of the base, with the top of the bar against the under side of the rail base. The larger end of the key 9 is then forced upwardly with a special tool or otherwise, between the other edge of the rail base and the fulcrum seat or bearing 4 with the 15 smaller more flexible end of the key, against the bearing 5, till the notch 10 snaps into engagement with the upper corner of the rail base. The smaller end of the key being thus forced upwardly against the bearing 5, subjects the key to tension or strain, tending to tip its wider end inwardly and downwardly and to cramp and hold it tightly between the opposing bearing and rail base. A slight longitudinal movement of the rail 25 towards the tie with which the abutment 6 engages, carries the key 9 with the adjacent end of the bar or yoke 1 towards the tie, thereby turning the bar into a position more or less oblique to the rail base and increasing its grip thereon, the end of the bar or yoke with the jaw 3, being prevented from advancing with the rail towards the tie, by the abutment 6.

The initial yielding grip of the anchor 35 on the rail base produced and maintained by the spring key 9, prevents the anchor from becoming loose and from being shifted back out of engagement with or operative relation to the tie by the jarring effect of 40 passing trains or other causes, and compensates for ordinary variations in the width and thickness of rail bases.

Referring to Figs. 4 and 6 inclusive, illustrating a modified construction of the 45 anchor, the tie abutment 6 is formed on the end of the bar or yoke 1' opposite the jaw 3, and is provided with the key deflecting or straining bearing 5', which may be cast integrally with and form a part of the abutment reinforcing web or flange 8'. The 50 tapering spring key 9' is substantially straight or but slightly curved, and may be driven or forced downwardly or upwardly into place between the fulcrum seat or bearing 4 and the opposite edge of the rail base, against the bearing 5', by which it is deflected and strained. Adjacent its smaller end the key may be slightly bent or recessed, as shown at 11 in Fig. 4, to engage with the 55 lower edge of the bearing 5' and thus prevent accidental displacement of the key upwardly after it has been forced into place.

In other respects the construction of this 60 form of anchor is substantially like that of the form shown in Figs. 1 to 3 inclusive,

and its mode of operation substantially the same.

With either form of the device the tie abutment 6 may be located at either end of the bar or yoke 1 or 1'. 70

I claim:

1. A rail anchor comprising a bar adapted to extend across the under side of a rail base and provided at one end with a jaw fitting over one edge of the rail base and at the 75 other end with key bearings, and a spring key adapted to be inserted and forced transversely of the rail into place against said bearings and the other edge of the rail base and acting when in place to grip the rail 80 base between the jaw and key with yielding pressure.

2. A rail anchor comprising a bar adapted to extend across the under side of a rail base and provided at one end with a jaw fitting 85 over one edge of the rail base and at the other end with key bearings, one bearing opposite the other edge of the rail base and the other bearing below the rail base, and a spring key adapted to be forced into place between 90 the rail base and opposite bearing and against the other bearing, and when in place to subject the bar to tension and draw the jaw towards the key with elastic pressure.

3. A rail anchor comprising a rigid bar 95 adapted to extend across the under side of a rail base and provided at one end with a jaw fitting over one edge of the rail base and at the other end with a key seat, and a spring key insertable transversely to the rail between 100 said seat and the other edge of the rail base and adapted when forced into place to be flexed and to exert a yielding tension through the bar against opposite edges of the rail base. 105

4. A rail anchor comprising a bar adapted to span the under side of a rail base and provided at one end with a jaw fitting over one edge of the rail base, at the other end opposite the other edge of the rail base with 110 a key seat and adjacent one end with a lateral tie abutment, and a spring key insertable transversely to the rail between said seat and the rail base and adapted when forced into place to be flexed and to yieldingly grip the rail base between the key and jaw. 115

5. A rail anchor comprising a rigid bar adapted to span the under side of a rail base and provided at one end with a jaw fitting 120 over one edge of the rail base, at the other end with a key seat opposite the other edge of the rail base and below the top of the bar with a key deflecting and straining bearing, and a spring key adapted when forced into 125 place between said seat and the adjacent rail base and against said deflecting bearing to yieldingly grip the rail base between the jaw and key.

6. A rail anchor comprising a bar adapted 130

- to span the under side of a rail base and provided at one end with a jaw fitting over one edge of the rail base, at the other end opposite the other edge of the rail base with a 5 key seat and below the top of the bar with a key deflecting bearing, and a spring key adapted to be forced into place between said seat and the rail base and against said bearing whereby it is strained and subjects the 10 bar to tension and clamps the rail base between the jaw and key, the key being formed with a positioning notch adapted when forced into place to engage with the adjoining edge of the rail base.
- 15 7. A rail anchor comprising a rigid bar adapted to span the under side of a rail base and provided at one end with a jaw fitting over one edge of the rail base, at the other end with a key seat opposite the other edge 20 of the rail base, and below the top of the bar with a key deflecting bearing, a spring key adapted to be forced into place between said seat and the other edge of the rail base and against said bearing and to yieldingly grip the rail base between the jaw and key, said bar being provided adjacent one end 25 with a lateral tie abutment tending when thrust against a tie by longitudinal movement of the rail to turn the bar obliquely to the rail and increase the grip of the key and jaw thereon.
8. A rail anchor comprising a bar adapted to span the under side of a rail base and provided at one end with a jaw fitting over one 30 edge of the rail base, at the other end with a key seat opposite the other edge of the rail
- base and below the top of the bar with a key deflecting bearing, and a tapering spring key adapted to be forced into place between 40 said seat and the adjacent edge of the rail base and against said bearing and to exert a yielding pressure against the rail base towards the jaw.
9. A rail anchor comprising a bar adapted to span the under side of a rail base and provided at one end with a jaw fitting over one edge of the rail base, at the other end with a key seat opposite the other edge of the rail base and below the top of the bar with a key deflecting bearing, and a curved spring 45 key adapted to be forced into place between said seat and the adjacent edge of the rail base and against said bearing and to exert a yielding pressure against the rail base towards the jaw.
10. A rail anchor comprising a rigid bar adapted to span the under side of a rail base and provided at one end with a jaw fitting over one edge of the rail base, and at the other end opposite the other edge of the rail 50 base with a key seat and below the top of the bar with a key deflecting and straining bearing, and a curved tapering spring key adapted to be forced under tension into place between the key seat and adjacent edge of 55 the rail base and against said deflecting bearing and to exert a yielding pressure against the rail base towards the jaw.

In witness whereof I hereto affix my signature.

LAURENCE J. BERKELEY.
